UNITED STATES PATENT OFFICE.

JAMES F. DE SPIRITO, OF BROOKLYN, NEW YORK.

FLUSHING DEVICE.

1,228,653.

Specification of Letters Patent.

Patented June 5, 1917.

Application filed August 21, 1913. Serial No. 785,938.

To all whom it may concern:

Be it known that I, JAMES F. DE SPIRITO, a citizen of the United States, residing at Brooklyn, in the county of Kings and State 5 of New York, have invented certain new and useful Improvements in Flushing Devices, of which the following is a specification.

This invention relates to flushing devices 10 particularly adapted for use in connection with water-closets, having for one of its objects to construct a device which will allow for the flow of water during a greater or less definite period of time.

15 Another object which this invention contemplates is the provision of a device of this character in which the initial flow of water opens the valve for allowing the water a direct flow into the bowl of the closet and at 20 the same time automatically closing the valve, after a predetermined quantity of water has been flushed.

Other objects as well as the nature, characteristic features and scope of my invention 25 will be more readily understood from the following description taken in connection with the accompanying drawings and pointed out in the claims forming a part of this specification.

30 Referring to the drawings:—

Figure 1 is a vertical sectional view of the device constructed in accordance with my invention; and

Fig. 2 is a cross sectional view taken on 35 the line 2—2 of Fig. 1.

In the drawings wherein is illustrated the preferred embodiment of this invention a casing 5 is provided which in the present instance is preferably of a cylindrical configuration, having formed in one of its sides a transverse inlet opening 6 which connects with a way 7, the latter being formed in the side of the casing and extending longitudinally therethrough, the mouth 45 of the way 7 being extended downwardly as indicated at 8 so as to facilitate the entrance of the water from the inlet 6 thereto. Arranged at a diametrically opposite point on the casing 5, from the way 7, is 50 a way 9 which has connection at one end with an outlet 10, the latter emptying into the bowl, while the opposite end of said way is in communication with the way 7 which is usually closed through the medium of 55 a construction which will be presently described.

The upper end of the casing 5 is provided with internal screw threads 11 which are engaged in threaded relation with the external threads of the bonnet or cap 12 which is arranged thereon, the cap 12 being provided with an annular depending flange 13 which extends in parallel relation to the body portion of the bonnet for a short distance, and has mounted between the inner 65 periphery thereof and the outer periphery of the body portion an elastic washer 14, to prevent the leakage of water from the interior of the casing 5 through the threads 11 and the threads of the bonnet 12 to the 70 exterior of the casing, as is sometimes the case. The bonnet 12 has formed on the inner end thereof an annular collar 15 which has formed therein registering apertures 16 which align with an aperture or opening 75 17 in a cap or plate 18, said opening 17 having connection with the way 9 of the casing 5. The cap 18 has depending therefrom a collar 19, the outer face of which extends 80 inwardly in spaced relation from the marginal edge of the cap, the inner face of said collar having screw threads formed thereon which engage with the screw threads of the valve chamber 20, the latter being so constructed as to provide a seat 85 21 for the coil spring 22. Mounted for vertical movement in the valve chamber 20, is a valve 23 which comprises a disk having an annular flange 24 provided on the upper face thereof and a concentric socket 25 90 which has rigid engagement with the free end of the handle stem 26. The opposite face of the valve disk has depending therefrom a stem 27 directly below the socket 25, said stem being engaged by the convolutions 95 of the coil spring 22. Formed at diametrically opposite points in the valve chamber 20 are openings 28 which connect with the interior of the casing 5, and permit the entrance of fluid through the way 7 and 100 into the way 9, when the valve 23 is disengaged from its seat.

The bonnet or cap 12 has formed therein a central opening in which is mounted a stuffing box 29 the latter being detachably 105 arranged therein and having depending therefrom an elongated annular flange 30 which is provided with alining apertures 31. The handle stem 26 extends through the stuffing box 29 and has mounted on the extreme upper end thereof a handle 32 which is for the purpose of unseating the valve 23 110

for allowing connection between the ways 7 and 9 as previously pointed out. To unseat the valve 23, the handle 32 is first rotated, and slight pressure then exerted thereon, which operation causes the complementary distorted faces of washers 5' to slide over each other; the lower of the washers which is shown in side elevation in Fig. 1 is fixedly secured to a shank depended from the handle 32, while the other washer, which is shown in section in Fig. 1, is fixedly engaged with the upper end of the casing 5, thereby permitting said shank to be forced downwardly for unseating the valve 23, and permitting said handle to be automatically raised to its normal position by the spring 22, as soon as pressure is released from the handle.

The casing 5 has threaded in the side thereof a needle valve 33 which has engagement through the way 7 for controlling the flow of water therethrough and into the interior of the casing, through an opening 34 which is formed therein, the needle valve 33 being enlarged exteriorly of the way 7 and provided with external screw threads which are in engagement with the internal threads of a cap 35. The end of the valve, beneath the external threads thereof, is squared as indicated at 36 for facilitating the actuating of the same.

Mounted for movement on the interior of the casing 5 and normally lying on a valve seat 37 which is formed in said casing adjacent the outlet 10 thereof is a valve 38 which is preferably of a substantially cylindrical configuration conforming to the interior of said casing, having a portion 39 thereof cut out, and the upper end thereof provided with screw threads for engagement with the washer retaining element 40, the latter comprising a disk having depending therefrom an externally screw threaded collar, said external threads being arranged in spaced relation from the peripheral edge of the disk. Extending over the top of the valve 38 and having engagement with the side thereof for a portion of its length, is a flexible washer 41 which may be of any suitable material, and is held in engagement therewith through the medium of the element 40 heretofore described. The opposite or lower end of the valve 38 has formed therein a threaded recess which is adapted for engagement with the threaded shank 42 of the member 43, the latter having movement through the outlet 10 of the casing, and having interposed therebetween and the valve 38 a washer 43' which is in engagement with the valve seat 37, when the valve is in a closed position.

In operation the water is allowed to flow through the inlet 6 from an external source of supply through the way 7, the pressure being controlled by the needle valve 33 therein, through the opening 34 and into

the casing 5, thus causing the valve 38 to be normally engaged on the seat 37. When it is desired to flush the water through the opening 10, the handle 32 is either turned or forced inwardly, which operation will unseat the valve 23, in view of the peculiar formation of plug which is advantageously illustrated in Fig. 1 causing said valve to operate in a vertical plane in a manner heretofore set forth. When the valve 23 is removed from its seat 44, the latter being formed on the end of the flange 30, and engages with the annular flange 24 of said valve, it will be seen that the water is allowed to flow through the openings 28 in the valve chamber 20 and upwardly through the apertures 31 of the elongated flange 30, and outwardly through the apertures 16 and 17 into the way 9, thence into the outlet 10 beneath the valve 38. By unseating the valve 23, it is seen that there is a diminution of pressure on the member 40 caused by the flowing of the water through the way 9, thereby permitting the valve 38 to be overbalanced by the pressure of the water in the inlet 6. The valve 38 is therefore unseated, permitting a direct flow of water through the inlet 6 and into the outlet 10 to the bowl of the closet. Only a limited amount of water will be allowed to flow directly through the inlet 6 and into the outlet 10, in view of the fact that after the valve 23 has been unseated, a constant pressure is exerted on the lower face thereof by the coil spring 22, which is under tension when said valve is unseated. It will be readily obvious that as soon as the flange 24 of the valve 23 is in engagement with the valve seat 44, communication will be cut off between the ways 7 and 9, thereby preventing the flow of water therethrough, and causing the chamber above the member 40 to be replenished for reseating the valve 38.

It will be understood that the above description and accompanying drawings comprehend only the general and preferred embodiment of my invention and that various minor changes in detail of construction, proportion and arrangement of the parts may be made within the scope of the appended claims and without sacrificing any of the advantages of my invention.

Having thus fully described my invention, what I claim as new and desire to secure by Letters Patent is:

1. A flushing device comprising the combination with a casing having an upper flange, a lower discharge end; an inlet passage opening into the upper portion of said casing, a connecting passage from the top of said casing to the outlet port thereof, and a valve closing communication between said inlet and said outlet ports, of a removable cap secured in said flange, a removable apertured plate positioned in said casing and

having an upstanding flange, a depending flange carried by said cap and resting upon the upper face of said plate to retain the latter in position, said flanges of the plate 5 and the cap having registering openings communicating with the upper end of said connecting passage formed in the casing, said cap having an upper fluid chamber formed therein, valve seat means carried by 10 said cap and extending through said upper fluid chamber, a valve chamber suspended from said plate and having communication with the upper portion of said casing and with the aperture through said plate, a 15 valve within said valve chamber and normally engaged with said plate and said valve seat means, means for resiliently retaining said second mentioned valve in normal position, a handle, and means adapted 20 to be operated by either downward or rotary movement of said handle to unseat the second mentioned valve and permit passage of fluid from the upper portion of said casing to the outlet port of said casing and 25 thereby allow upward movement of the first mentioned valve to open a direct communication between the inlet and outlet ports of said casing.

2. A flushing device comprising a casing 30 having an open upper end and a lower discharge end, said casing having an inlet at one side, a cap for the open upper end of said casing, an apertured plate positioned between said upper end of the casing and

said cap, a valve chamber suspended from 35 said plate and communicating with the aperture therein, said valve chamber having openings forming communication between the interior thereof and the upper portion of said casing, a stuffing box mounted in said cap, said stuffing box having a depending flange provided with side openings, a valve seat secured between said depending flange and said apertured plate, said cap having a depending flange surrounding and spaced from the hollow depending flange of 40 said stuffing box and provided with openings, a releasing valve within said valve chamber, means for resiliently retaining said valve in engagement with said seat, a 45 valve normally closing communication between the inlet passage and the outlet passage of said casing, said casing having a passage leading from the portion of said casing above said plate to the lower end of 50 said casing below the second mentioned valve, and means for forcing said releasing valve away from said seat to permit fluid from the upper portion of said casing to enter the hollow depending flange of the stuffing 55 box.

In testimony whereof I affix my signature in presence of two witnesses.

JAMES F. DE SPIRITO.
